UNITED STATES PATENT OFFICE.

FELIX M. LOCHER, OF VISALIA, CALIFORNIA.

CULINARY IMPLEMENT.

1,376,346.

Specification of Letters Patent. Patented Apr. 26, 1921.

Application filed August 9, 1920. Serial No. 402,190.

To all whom it may concern:

Be it known that I, FELIX M. LOCHER, a citizen of the United States, residing at Visalia, in the county of Tulare and State 5 of California, have invented certain new and useful Improvements in Culinary Implements; and I do declare the following to be a full, clear, and exact description of the invention, such as will enable others 10 skilled in the art to which it appertains to make and use the same.

This invention relates broadly to improvements in culinary implements, and it has more particular reference to a device of this 15 class which is especially designed for shredding cocoanuts, although it is not to be restricted to this particular use.

The principal object of the invention is to provide a device of this class which is simple and effective, strong, durable, and inexpensive to manufacture.

Another object of the invention is to provide a device of the above mentioned type which includes a seat board to be placed 25 on a chair seat, this board being provided with a tongue to extend beyond the front edge of the chair seat, and on this tongue is a cutter. With this construction the user seats himself on the seat board to hold the 30 device rigid, thus positioning the cutter in an extremely advantageous position for shredding cocoanuts and the like.

Other objects and advantages of the invention will be apparent during the course 35 of the following description.

In the accompanying drawings forming a part of this specification and in which like numerals are employed to designate like parts throughout the same:

40 Figure 1 is a top plan view of an implement constructed in accordance with my invention, the same being shown in position for use on a chair bottom.

Fig. 2 is a central vertical sectional view 45 thereof taken on the line 2—2 of Fig. 1, looking in the direction of the arrows.

As before stated, my device, when being used, is designed to be placed on a chair bottom while the operator sits on it to hold 50 it in position for convenient and advantageous use. In the drawings, I have shown a chair 1 which may be of the usual construction and which may be provided with either a square or any other shaped bottom 55 2.

My shredder comprises a flat board 3 of

wood or other material preferably circular in shape, the same including an extension which constitutes a neck 4 which, when in position, is intended to extend beyond 60 the front edge of the chair bottom 2. Secured in any suitable way to this tongue is a cutter 5. This cutter may be of any construction, but I prefer to employ a substantially rectangular metal plate for the 65 purpose and detachably secure the inner end of this plate to the tongue 4 by bolts 6. The plate is so positioned that the front end thereof extends beyond the outer extremity of the tongue and this extended 70 part of the plate is curved or semi-circular, and is bent upwardly as shown in Fig. 2, this upwardly bent portion being serrated to provide a plurality of cutting teeth 7. A cutter of this construction will effectively 75 scrape the meat from the cocoanut, and due to the peculiar curvature of the teeth and shape of the outer edge thereof, it will conform to the interior of the nut and effectively remove all of the meat, which 80 could not be done with a flat and straight member.

To operate the device, the seat board 3 is placed upon the chair bottom 2 in the manner illustrated in Fig. 1, that is, it is so 85 placed on the chair that the neck 4 is permitted to extend outwardly beyond the front edge of the chair bottom. The operator then seats himself on this board 3 as if sitting in a chair, and takes one half of the 90 cocoanut (the cocoanut should be cut longitudinally to insure effective shredding of the meat with this device) in one hand and proceeds to scrape the meat therefrom by forcing it back and forth across the teeth 95 7 as is obvious. As before stated, the teeth are so curved and bent upwardly that they will effectively remove every bit of the meat from the shell.

It is thought that the foregoing brief explanation of the operation and use of my device is sufficient to enable persons skilled in the art to which this invention relates to obtain a clear understanding of the same; therefore, a more lengthy description is 100 deemed unnecessary.

Since the best results can, no doubt, be obtained with the construction shown and described, this construction is taken as a preferred embodiment of my invention; but 110 I wish it to be understood that minor changes in the shape, size, and arrangement

of parts may be resorted to without departing from the spirit of the invention or the scope of the subjoined claims.

I claim:

5. 1. A cocoanut shredder comprising a support, and a substantially rectangular metal plate secured to the upper face thereof and extending beyond one end, the outer edge of this plate being curved transversely, bent 10 upwardly, and serrated to provide a plurality of cutting teeth.

2. A cocoanut shredder comprising a substantially circular flat seat-board adapted to rest on the bottom of a chair, said board including a reduced relatively narrow forwardly extending neck, which when in position, extends beyond the front edge of the chair bottom, and a cutter secured to the outer extremity of said neck. 15

In testimony whereof I have hereunto set 20 my hand.

FELIX M. LOCHER.
